UNITED STATES PATENT OFFICE.

ZERNE O. RARRICK, OF TOLEDO, OHIO, ASSIGNOR TO THE RANSOM & RANDOLPH COMPANY, OF TOLEDO, OHIO, A CORPORATION OF OHIO.

CARBURETED-AIR-GAS APPARATUS FOR BLOWPIPES.

Application filed July 22, 1921. Serial No. 486,687.

To all whom it may concern:

Be it known that I, ZERNE O. RARRICK, a citizen of the United States, and resident of Toledo, in the county of Lucas and State 5 of Ohio, have invented a certain new and useful Improvement in Carbureted-Air-Gas Apparatus for Blowpipes, of which the following is a full, clear, concise, and exact description, reference being had to the accompanying drawings, forming part of this 10 specification.

My invention relates to an apparatus that is especially adapted to supply a combustible mixture of air and vaporized hydro- 15 carbon to a blowpipe of the type employed by dentists. The apparatus of my invention is particularly adapted for use in all kinds of fine soldering and for melting the various base and precious metals used in 20 dental restorations.

In years past, gasoline blowpipes have been very popular with dentists, the flame from such a blowpipe being admirably suited to dental purposes. It has been found, 25 however, that the carbureting device used in connection with those styles of gasoline blowpipe equipments heretofore used by dentists are incapable of successfully handling the comparatively low grade gasoline 30 now on the market.

It is the principal purpose of my invention to provide a carburetor that will successfully handle the comparatively poor 35 grades of gasoline now available, and one that may be readily adjusted by the operator to secure the best possible mixture at the blowpipe under all operating conditions. Other objects of the invention will appear 40 as the following detailed description progresses.

In the accompanying drawings illustrating my invention, Figure 1 is a top plan view of a gasoline blowpipe appliance embodying my invention,

45 Figure 2 is a side elevational view thereof, Figure 3 is a vertical section taken on the line 3—3 of Figure 1,

Figure 4 is a vertical section taken on the line 4—4 of Figure 3,

50 Figure 5 is a section taken on line 5—5 of Figure 4,

Figure 6 is a section taken on the line 6—6 of Figure 4,

Figure 7 is a section taken on the line 7—7 of Figure 4, and

Figure 8 is a diagram in elevation which graphically illustrates the changes in the functioning of the carburetor which result from manipulation of the controlling handle.

Similar characters of reference refer to similar parts throughout the several views.

Referring first to Figures 1 to 3 inclusive, at 10 I have illustrated a tank adapted to contain a supply of gasoline or other liquid hydrocarbon. The supply of gasoline is renewed or replenished as required through a filling cup 11, the opening through this filling cup being normally closed in any suitable manner, as, for instance, by a 70 threaded plug 12.

The tank 10 is provided in the top thereof with an opening 13 and threaded into this opening is a casting 14 which seats upon a gasket 15. Threaded into the casting 14 are the nipples 16 and 17 which respectively 75 constitute passages for the intake of air and the outlet of combustible mixture. The nipple 16 co-operates with one end of a flexible tube 18, the other end of this tube being connected with a source of air supply as, for instance, an ordinary foot bellows (not shown). Nipple 17 co-operates with one end of a flexible tube 19 which leads to any suitable form of blowpipe (not 80 shown).

Referring now to Figure 5, it will be noted that air intake nipple 16 communicates with a bore 20, a bore 21 affords communication between bore 20 and a bore 22, 90 bore 22 being parallel to and in the same horizontal plane with the bore 20. The outer end of bore 21 is closed in any suitable manner, conveniently by the threaded plug 23. One end of bore 22 communicates directly with combustible mixture outlet nipple 17, and the other end of said bore communicates with the space within an imperforate cap 24 which is tightly threaded upon a boss 25 projecting laterally from casting 14. A second bore 26 is formed in boss 25 (Figure 4). Bore 26 lies below and is parallel with bore 22. The bore 26 extends inwardly from cap 24 and intersects a vertical bore 27. The inner or left hand 105 end of bore 26 (Figure 4) communicates

with a vertical bore 28. Bore 28 communicates at its lower end with the space above the liquid in the tank 10, and at its upper end communicates with the bore 22 at a point adjacent the inner end of the combustible mixture outlet nipple 17.

Disposed in the vertical bore 27 is a rotatable valve element 29 which is provided with a longitudinal vertical bore 30. The upper end of bore 30 terminates short of the upper end of the valve element, and at its lower end communicates with the passage through a tube 31. The upper end of the tube 31 is threaded tightly into the lower end of the valve element 29 (Figure 4) and the lower end of said tube lies near the bottom of tank 10, or, at any rate, terminates a considerable distance below the normal level of liquid fuel in tank 10.

20 Valve element 29 is provided with a transverse bore affording ports 32 and 33 (Figures 4 and 6). Port 32 is adapted to afford communication between bore 26 and the upper end of valve element bore 30. It will be noted that the outer surface of the valve element is milled at the port 32 so that the latter may communicate with the right hand portion of bore 26 (Figure 6) throughout a full 90 degree movement of the valve element. Bore 33 is adapted to afford communication between valve element bore 30 and the left hand portion of bore 26 (Figure 4) when the valve element is in the position illustrated in Figures 4 to 6, and 35 through the major portion, but not all, of the full 90 degree movement of which the valve element is capable. Valve element 29 is also provided with a transverse bore 34 which is adapted to afford communication 40 between the right and left hand portions of bore 22 (Figures 4 and 5) during approximately 35 degrees of the total 90 degrees of movement of which the valve element 29 is capable.

45 I now call attention to a port 35 which is formed in valve element 29 at a point slightly above the lower end thereof, it being the purpose of this port 35 to afford communication between valve element bore 30 and a vertical channel 36 (Figures 3 and 7). The lower end of this channel communicates directly with the space above the liquid hydrocarbon in tank 10. Port 35 affords communication between bore 30 and channel 36 55 through approximately 60 degrees of movement of the valve element 29.

Valve element 29 is provided with a reduced upper portion 29^a extending upwardly through a bore 27^a which is of less diameter than bore 27 but coaxial therewith. The reduced upper end of the valve element is pinned to an operating handle 37, which is capable of movement through an angle of 90 degrees determined by the stop pins 38 and 65 38'. The operating handle is preferably

provided with a pointer 37^a which co-operates with suitable scale markings 39. The ends of the scale are preferably provided with suitable indicia such as the words "Red" and "Blue" so that the operator may know in which direction to operate the handle to effect any desired change in the character of the blowpipe flame.

It will be noted that the boss 25 lies within a tubular flange 40 which is of greater diameter than said boss but concentric therewith. This arrangement affords an annular chamber between boss 25 and flange 40. One end of the annular chamber communicates with the atmosphere. The other end thereof communicates through a small horizontal bore 41 with the upper end of a vertical bore 42. The lower end of the vertical bore 42 communicates directly with the space above the liquid hydrocarbon in tank 10. The said annular chamber is provided at its outer end with an annular burner screen 43 which is conveniently formed of perforated metal. Screen 43 is clamped in position by cap 24. If desired, an auxiliary or safety screen may be placed in the annular chamber as indicated at 44.

Having now described the construction of the device of my invention, I shall proceed to explain the operation thereof.

Prior to using the device, a suitable quantity of liquid hydrocarbon is placed in tank 10. A blowpipe is connected with combustion mixture outlet nipple 17 through tube 19, and a suitable bellows is connected with air intake nipple 16 through tube 18. Now let us assume that at starting the operating handle has been moved to the position wherein it lies against the stop pin 38'. It will be understood that the drawings illustrate the valve member in the position occupied thereby when the operating handle 37 lies midway between the stop pins. With the handle against the stop pin 38', air entering the carburetor through air intake nipple 16 flows through bores 20, 21 and 22 into cap 24. At this time valve element bore 34 is out of registry with bore 22 and thus none of the incoming air can pass through said valve element bore 34. Ports 33 and 35 are likewise closed at this time. The incoming air passes from cap 24 into bore 23, and thus through port 32 into valve element bore 30, and thus downwardly through tube 31. The air escaping from the lower end of tube 31 bubbles up through the liquid hydrocarbon and becomes saturated with the more volatile constituents of the hydrocarbon. The major portion of the air and hydrocarbon vapor which collects in the upper portion of tank 10 flows upwardly through bore 28 and then passes through combustible mixture outlet nipple 17 and flexible tube 19 to the blow pipe. A comparatively small portion of the combustible

mixture collected in the upper portion of the tank passes through bores 42 and 41 into the annular chamber around boss 25, and serves to sustain a flame at screen 43. The vapor escaping through screen 43 is preferably ignited as soon as sufficient combustible mixture has been created in the upper portion of tank 10 to sustain a flame at the screen. The flame at screen 43 heats cap 24 to a high temperature with the result that all air passing through the cap 24 is likewise heated to a comparatively high temperature.

The air heated in cap 24 and subsequently discharged into the lower end of tank 10 causes effective volatilization of the liquid hydrocarbon through which it passes, with the result that a very rich hydrocarbon vapor is created in the top of tank 10. Unless the liquid hydrocarbon which happens to be in tank 10 has previously been deprived of nearly all its volatile constituents, the operator will usually find that with the operating handle against pin 38', the combustible mixture which is supplied to the blowpipe is too rich to afford an effective flame at the blowpipe.

To correct the blowpipe flame, the operator moves the operating handle in a clockwise direction (Figure 8). After the operating handle has been moved through a very few degrees as just explained, the port 33 begins to afford communication between bore 30 and the left hand end of bore 26 (Figure 4). Under this condition a portion of the heated air passing into the bore 30 escapes directly into the bore 28 and becomes a part of the combustible mixture of hydrocarbon and air which is supplied to the blowpipe. The percentage of heated air which passes directly to the blowpipe without passing through the liquid hydrocarbon is, of course, governed by the disposition of bore 33 with respect to the left hand end (Figure 4) of bore 26.

By moving the operating handle approximately 30 degrees away from the stop pin 38', the valve element 29 is brought to a position wherein the valve element port 35 begins to permit a portion of the heated air flowing through bore 30 to escape from said bore and pass downwardly through channel 36 into the combustible vapor in the top of tank 10.

When the operating handle is moved approximately 55 degrees away from the stop pin 38', the valve element bore 34 begins to come into registry with the right and left hand portions (Figure 5) of bore 22, and begins to permit a portion of the cold air entering through the air intake nipple 16 to pass directly from bore 22 into the combustible mixture outlet nipple 17 without passing through the heating cap 24.

Shortly before the operating handle is

moved into contact with stop pin 38, the port 33 moves entirely out of registry with the left hand portion of bore 26 (Figure 4), and thus prevents the escape of heated air from bore 30 at this point.

Generally speaking, when the operator discovers that his blowpipe flame is poor in quality, he manipulates the operating handle until he secures satisfactory results at the blowpipe. If the flame appears to be red or smoky, he knows that the quality of his blowpipe flame will be improved by moving the operating handle pointer away from the "Red" end of the scale, and he also knows that if he secures at the blowpipe the impoverished sort of flame which results from too lean a mixture, that the blowpipe flame may be improved by moving the operating handle pointer away from the "Blue" end of the scale.

The carbureting device of my invention has been found to operate successfully upon all grades of commercial gasoline and other suitable hydrocarbons that are available at the present time. By manipulating the controlling handle, the operator is enabled always to cause the carburetor to function in the fashion which is best suited to the particular grade of hydrocarbon with which he is working.

One very important and valuable advantage of the apparatus herein shown and described is the fact that the operator, by simple manipulation of the adjusting handle, may accurately and selectively regulate the temperature of the blow pipe flame. The advantages in this respect which are afforded by my apparatus are believed to be without parallel in the prior art.

It will, of course, be understood that the improvements of my present invention may readily be incorporated in a gasoline appliance of the well known "Brophy" type (U. S. Letters Patent 760,099, granted to R. C. Brophy, May 17, 1904). Such an adaptation of my present invention is illustrated in my prior Patent No. 1,447,571 issued March 6, 1923.

While I have illustrated a preferred embodiment of my invention, it will be understood that I in no way limit myself to the specific arrangement and construction of parts herein shown and described, but desire to cover all equivalent constructions falling within the terms or spirit of the appended claims.

Having thus described my invention, what I claim as new and desire to secure by Letters Patent is:

1. A carbureted air gas apparatus for blowpipes comprising a stationary receptacle for liquid fuel, a passage through which uncarbureted air is introduced into the liquid fuel below the level thereof, said passage comprising two parallel portions,

an annular chamber around said parallel portions, means for conducting a portion of the carbureted air from above the level of liquid fuel directly to said annular chamber 5 to sustain a flame which heats the parallel portions in said passage, and means for conducting carbured air gas from the top of said receptacle.

2. In apparatus for producing a combustible carbureted air gas solely by bubbling air through a volatile hydrocarbon fuel, the combination of a stationary receptacle adapted to receive an initial charge of gasoline or like hydrocarbon fuel, and to be 10 thereafter closed to the admission of fuel, a valve housing mounted on said receptacle, a conduit supplying air under pressure to said valve housing, an air inlet passage in said valve housing for conducting said compressed air down into said relatively inert body of fuel for bubbling the compressed air up through said fuel, a second air inlet passage in said valve housing for conducting said compressed air into the upper area 15 of said receptacle, a gas outlet passage in said valve housing adapted to be connected with the point of use, a shunting air passage for admitting said compressed air to said gas outlet passage, a valve in said 20 valve housing co-operating with said passages to control the supply of compressed air above and below the top of said fuel, and to control the outlet of gas and the admission 25 of compressed air thereto, and a burner passage in said valve housing drawing directly from the upper part of said receptacle for supplying a preheating flame heating a portion of said valve housing traversed by one 30 of said air passages.

3. A carbureted air gas apparatus for blowpipes, comprising a receptacle adapted to contain a body of liquid fuel, said receptacle comprising a head portion, an air tube depending from said head portion into the 35 body of liquid fuel for bubbling air up through said fuel, an air supply duct in said head portion, an air supply conduit connecting with said air duct for supplying air under pressure thereto, a preheating duct in 40 said head portion adapted to receive air from said air supply duct and discharge the air to said air tube, a burner duct in said head portion communicating with the upper area of said receptacle, said burner duct 45 being adapted to sustain a preheating flame in proximity to said preheating duct, and an outlet duct in said head portion for receiving the air gas formed in said receptacle 50 for conducting the same to a blowpipe.

4. Carbureted air gas apparatus for blowpipes comprising a receptacle adapted to contain a body of liquid fuel, said receptacle comprising a head portion, an air tube depending from said head portion below the 55 liquid level in said receptacle for bubbling

air up through said liquid fuel, an air supply duct in said head portion adapted to be connected to a source of air supply, a pre-heating duct in a said head portion communicating with said air supply duct, a valve in said head portion controlling communication between said preheating duct and said air tube, a burner duct in said head portion for receiving the combustible mixture from the upper part of said receptacle 75 and for maintaining a preheating flame adjacent said preheating duct, and an outlet duct in said head portion withdrawing the air gas from the upper portion of said receptacle and adapted to communicate with 80 a gas supply conduit leading to the blowpipe.

5. A carbureted air gas apparatus for blowpipes and the like comprising a receptacle adapted to contain a body of liquid fuel, said receptacle comprising a head portion, an air tube depending from said head portion below the liquid level in said receptacle for bubbling air up through the fuel, an air supply duct in said head portion, a preheating duct in said head portion communicating with said air supply duct, a burner duct in said head portion adapted to be supplied with combustible gas from the upper portion of said receptacle and for maintaining a preheating flame adjacent 95 said preheating duct, an outlet duct in said head portion for drawing the air gas formed from the upper part of said receptacle and adapted for connection to a gas supply conduit, and valve means in said head portion adapted to shunt a part of the heated air from said preheating duct to said outlet duct.

6. Carbureted air gas apparatus for blowpipes and the like comprising a receptacle adapted to contain a body of liquid fuel, said receptacle comprising a head portion, an air tube depending from said head portion below the liquid level in said receptacle for bubbling air up through the fuel, an air supply duct in said head portion, a preheating duct in said head portion communicating with said air supply duct, a burner duct in said head portion drawing combustible gas from the upper portion of said receptacle 110 for maintaining a preheating flame adjacent said preheating duct, and valve means in said head portion operative selectively to direct the heated air from said preheating duct into said air tube or into the upper portion of said receptacle above the liquid level.

7. Carbureted air gas apparatus for blowpipes and the like comprising a receptacle adapted to contain a body of liquid fuel, said receptacle comprising a head portion, an air tube depending from said head portion below the liquid level in said receptacle for bubbling air up through the liquid fuel, an 115

- air supply duct in said head portion, a pre-heating duct in said head portion communicating with said air supply duct, said air tube receiving the heated air from said pre-heating duct, an outlet duct in said head portion for drawing the air gas formed from the upper part of said receptacle and adapted for connection to a gas supply conduit, and valve means in said head portion operative to place the air supply duct in communication with said outlet duct for directing relatively cold air into said outlet duct instead of to said preheating duct.
8. Carbureted air gas apparatus for blow-pipes and the like comprising a receptacle adapted to contain a body of liquid fuel, said receptacle comprising a head portion removably mounted in the upper end of said receptacle, a rotatable valve in said head portion, an air tube depending from the lower end of said valve below the liquid level in said receptacle for bubbling air up through the liquid fuel, an air supply duct in said head portion adapted for connection to an air supply conduit leading from a source of air under pressure, a preheating duct in said head portion communicating with said air supply duct, a burner duct in said head portion drawing combustible gas from the upper part of said receptacle and for maintaining a preheating flame adjacent said preheating duct, a port in said valve controlling communication between said preheating duct and said air tube, a second port in said valve for admitting preheated air to the upper part of said receptacle above the liquid fuel level, an outlet duct in said head portion for drawing combustible gas from the upper portion of said receptacle and adapted for connection to a gas supply conduit leading to the blowpipe or other point of use, a third port in said valve for admitting preheated air from said preheated duct to said outlet duct, and a fourth port in said valve for admitting relatively cold air supplied through said air supply duct to said outlet duct instead of to said preheating duct.
9. Carbureted air gas apparatus for blow-pipes and the like, comprising a receptacle adapted to contain a body of liquid fuel, an air tube in said receptacle for discharging air therein below the liquid fuel level, an air supply duct associated with said receptacle, a preheating duct communicating therewith, a burner duct leading from said receptacle for drawing combustible gas therefrom for maintaining a flame in proximity to said preheating duct, a gas duct extending from the upper part of said receptacle, and a valve element co-operating with said preheating duct to control the delivery of preheated air to said receptacle and having means cooperating with said outlet duct for controlling the admission of hot or cold air thereto.

In witness whereof, I hereunto subscribe my name this 28 day of June, 1921.

ZERNE O. RARRICK.
